UNITED STATES PATENT OFFICE.

CHARLES F. HUMPHREYS, OF LANCASTER, PENNSYLVANIA, ASSIGNOR TO ARM-
STRONG CORK COMPANY, OF LANCASTER, PENNSYLVANIA, A CORPORATION OF
PENNSYLVANIA.

DESIGN FOR LINOLEUM OR SIMILAR HARD-SURFACED FLOOR COVERING.

Application filed November 13, 1926. Serial No. 19,701. Term of patent 7 years.

To all whom it may concern:

Be it known that I, CHARLES F. HUMPHREYS, a citizen of the United States, residing at Lancaster, county of Lancaster, and State of Pennsylvania, have invented a new, original, and ornamental Design for Linoleum or Similar Hard-Surfaced Floor Covering, of which the following is a specification, reference being had to the accompanying drawing, forming part hereof.

The figure is a plan view of a portion of linoleum or similar hard surfaced floor covering, showing my design, it being under-

stood that the design in the representative illustration is repeated throughout the extent of the linoleum or similar hard surfaced floor covering.

The design is preferably executed in various shades or colors, although the particular shadings employed in the illustration are not intended to indicate any particular colors.

I claim:

The ornamental design for linoleum or similar hard surfaced floor covering, substantially as shown and described.

CHARLES F. HUMPHREYS.
